INVENTOR

Samuel Blaine Stine
By Archworth Martin,
Attorney

UNITED STATES PATENT OFFICE

SAMUEL BLAINE STINE, OF OSCEOLA MILLS, PENNSYLVANIA

SCREEN STRUCTURE

Application filed April 10, 1928. Serial No. 268,864.

My invention relates to screen structures, and more particularly to screens of plate form, such as are employed in connection with the pans of shale crushing mills, for example, although it may be employed in various other ways.

One object of my invention is to provide a screen structure that will have greater life than those of various forms heretofore employed, by reason of the fact that those portions of the screen which are commonly subjected to greatest wear are so formed that they will have a life substantially equal to the life of the remaining portions of the screen.

Another object of my invention is to provide a screen structure that is of greater rigidity than the screens of similar sizes, as heretofore constructed.

A further object of my invention is to provide means for securing a screen plate to its supporting frame, of such form that the screen plate and its frame will be securely maintained in assembled relation notwithstanding the wearing-down of the screen plate in use.

Still another object of my invention is to simplify and improve generally the structure and wearing qualities of screen devices.

Some of the forms which my invention may take are shown in the accompanying drawing, wherein Figure 1 is a view, partially in plan and partially in section, of a screen plate and its supporting frame; Fig.

2 is a side elevational view of the structure of Fig. 1; Fig. 3 is a view taken on the line III—III of Fig. 1; Fig. 4 is a view similar to Fig. 3, but showing a modification of the structure of Figs. 1 to 3.

Referring to Figs. 1 to 3, perforated metallic screen plates 5 and 6 are welded to the upper edge of a band or hoop 7. The metallic screen plates 5 and 6 rest upon a frame or base 8. The band 7 is disposed peripherally of the frame 8 and is secured thereto by means of rivets 9.

As shown more clearly in Fig. 2, the screen plate 5 is of greater thickness than the plate 6. The inner portions of the screen plates employed in connection with crushing mills

wear much more rapidly than the outer portions of said plate, with the result that where a single plate of uniform thickness is employed instead of plates 5 and 6, such plate has to be discarded long before the outer portion thereof has become worn out, owing to the wearing out of the inner portion. By my arrangement, it is not necessary to stop crushing and screening operations until after substantially the entire screening surface has become worn down.

To compensate for the difference in thickness of the plates 5 and 6, I provide offsets in the band 7 and the frame 8, as indicated at 10 in Fig. 2. To provide still greater rigidity in the structure, I weld blocks 11 to the undersides of the plates 5 and 6, and provide complementally-formed recesses in the frame 8, into which the blocks 11 fit. Counter-sunk or tapering holes 12 extend through the frame 8, the blocks 11 and the screen plates 5 and 6, as shown more clearly in Fig. 3, and rivets 13 are fitted into such holes.

It will be seen that the screen plates and the frame 8 are rigidly held in assembled relation by means of the band 7, the rivets 9, the blocks 11, and the rivets 13, and that these fastening means are so disposed as to be unaffected by the wearing-down of the screen plates in use, so that such screen plates will not become loose upon their frames, even when they have been almost completely worn down.

Referring to Fig. 4, a band or band sections 7^a are welded to the screen plates 5 and 6 at points removed from the periphery of such plate, so that they will fit against the inner sides of a frame 8^a, instead of against the outer sides thereof, as in Figs. 1 and 3. The structure of this modification may be otherwise similar to the structures of Figs. 1 to 3.

It will be understood that the drawing is representative of a segment-like portion of a screen, such as is employed in connection with crushing mill pans, and that the other portions of a complete screen structure may be of the form shown in the drawing.

I claim as my invention:—

1. Screen structure adapted for relative rotative movement with respect to a scraper, comprising an outer screen portion, and an inner screen portion of greater thickness than the outer portion.
2. Screen structure adapted for relative rotative movement with respect to a scraper, comprising an outer screen portion, and an inner screen portion of greater thickness than the outer portion, the spacing between the slots of one portion being substantially the same as the spacing of the slots in the other portion.
3. Screen structure comprising a frame, a screening plate mounted on said frame, and a band-like projection depending from the underside of the plate and abutting against the vertical edges of the frame, the screening plate entirely overlying the uppermost surface of the frame.
4. Screen structure comprising a frame having a hole extending vertically through one side thereof, a screen plate disposed against said side of the frame and having a lug extending into said hole, and a rivet-like member extending through the hole and the lug for securing said lug in the said hole.
5. Screen structure comprising a frame having a hole extending through one side thereof, a screen plate disposed against said side of the frame and having a lug extending into said hole, and means comprising a rivet extending through a countersunk hole in the said lug and through the hole in the frame for securing the plate to the frame.

In testimony whereof I, the said SAMUEL BLAINE STINE, have hereunto set my hand.

SAMUEL BLAINE STINE.
